UNITED STATES PATENT OFFICE.

ALEXANDER DOM, OF MOUNT HEALTHY, OHIO.

CLAMP-FILE.

SPECIFICATION forming part of Letters Patent No. 409,142, dated August 13, 1889.

Application filed June 17, 1889. Serial No. 314,615. (No model.)

To all whom it may concern:

Be it known that I, ALEXANDER DOM, a citizen of the United States, residing at Mount Healthy, in the county of Hamilton, State of 5 Ohio, have invented certain new and useful Improvements in Clamp-Files, of which the following is a specification, reference being had to the accompanying drawings, in which—

Figure 1 is a perspective view of my improved file as viewed from the rear end thereof. Fig. 2 is a top view of the clamp-board broken away and the spring-support connected thereto, the clamp being removed. Fig. 3 is 10 a side view of my improved file in an operative position.

The object of my invention is to provide a temporary file which shall be cheap of manufacture and at the same time simple and effective in operation. The file may also be 15 advantageously used for retaining a loose package of paper in position while being written on in tablet form.

My improved file is preferably constructed as follows: The clamp proper A is so stamped 20 or otherwise formed as to provide the side extensions or lugs $a a$ and a central rearwardly-inclined bearing-lug a' , all integral with the body of the clamp. The rearwardly-inclined lug a' is preferably provided with two grooves 25 $a^2 a^2$, in which the ends of the spring-support rest when in an operative position. The clamp-shaft B is suitably connected to the side lugs $a a$ of the clamp proper.

The operating spring-support is formed 30 from one continuous piece of spring-wire in such a manner as to form the base D, coiled bearings $d d$, and extensions $d' d'$, as shown, the end portions of the base being connected to the clamp-board E in any suitable manner.

40 The clamp-shaft B is passed through the coiled bearings $d d$ of the spring-support and the ends of said shaft are then riveted or otherwise suitably secured to the lugs $a a$. The end portions of the extensions $d' d'$ of this 45 spring-support bear against the under face of

the central rearward projection a' in the grooves $a^2 a^2$, which has the tendency, through the resiliency of the spring, to continually force the front portion of the clamp A down on the clamp-board and securely retain any 50 papers that may be inserted between said clamp and board.

To release or replace any paper in the file, all that is required is to put pressure on the extension a' of the clamp, which will release 55 the front portion of the clamp from off the paper or board.

The advantages of my improved file are apparent. By reason of the afore-described construction the cost of manufacture is lessened, 60 in that no box, receptacle, or housing is required for the spring. The construction of the spring-support is such that it acts as a support and bearing for the clamp-shaft.

What I claim as new, and desire to secure 65 by Letters Patent, is—

1. In combination with the clamp-board and clamp, the latter having the side lugs and central rearward projection integral therewith, the spring-support connected to said clamp-board and so bent as to form a base-support and journal-bearings for the clamp-shaft, the latter passing through the coiled portions of 70 said spring, the ends of said spring bearing against the under face of the extension of the 75 clamp, substantially as set forth.

2. A file consisting of a clamp-board E, clamp A, the latter having the side lugs $a a$, and rearward projection a' , having the grooves $a^2 a^2$ therein, in combination with the spring-support 80 consisting of a base D, coiled bearings $d d$, and projections $d' d'$, the clamp-shaft B passing through the coiled portions $d d$, the ends of said shaft being connected to the side lugs $a a$ of the clamp, substantially as described. 85

ALEXANDER DOM.
